(57) **CLAIM**

The ornamental design for an article of footwear, as shown and described.

DESCRIPTION

FIG. 1 is a perspective view of an article of footwear showing my new design;

FIG. 2 is a lateral side view thereof;

FIG. 3 is a medial side view thereof;

FIG. 4 is a rear view thereof;

FIG. 5 is a top view thereof; and,

FIG. 6 is a bottom view thereof.

The dashed broken lines and the halftone areas bounded by the dashed broken lines illustrate portions of the article of footwear that form no part of the claimed design.

The word mark "SOREL" shown in the figures is a registered trademark of Sorel Corporation and forms no part of the claimed design. The "bear" design mark shown in the figures is a registered trademark of Sorel Corporation and forms no part of the claimed design.

1 Claim, 6 Drawing Sheets
